UNITED STATES PATENT OFFICE.

LESLIE CARL DUTRO, OF LONG BEACH, CALIFORNIA.

OIL CUP.

Application filed September 10, 1923. Serial No. 662,026.

To all whom it may concern:

Be it known that I, LESLIE C. DUTRO, a citizen of the United States, and a resident of Long Beach, in the county of Los Angeles and State of California, have invented a new and Improved Oil Cup, of which the following is a full, clear, and exact description.

This invention relates to oil cups and has for an object to provide an improved construction which is particularly adapted for oiling rapidly moving parts without wasting the oil.

Another object in view is to provide an oil cup in which the oil is fed partly by a siphon effect whereby the cup may be used on crank pins and other rapidly moving members without throwing or discharging more oil than desired.

20 In the accompanying drawing—

Figure 1 is a longitudinal vertical section through an oil cup, disclosing an embodiment of the invention, the same being taken on line 1—1 of Figure 2.

25 Figure 2 is a transverse sectional view through Figure 1, approximately on line 2—2.

Referring to the accompanying drawing by numerals, 1 indicates the body of a cup 30 which may be of glass or other material and which is provided with a cap 2. A gasket 3 provides a tight joint between the body 1 and cap 2. A tubular member 4 extends through cap 2 and also through the bottom 35 into the fitting 6 which is screwed thereon. Suitable gaskets 7 and 8 are provided for maintaining a tight joint between the respective parts just described. The tubular member 4 having a partition 13 forms a 40 combined well and feeding tube, said tube being locked in place by a suitable nut 9 and provided with a closing cap 10. The well or tube 4 is provided with a number of apertures 11 at different points whereby the oil 45 may readily flow in or out. A feed or discharge pipe 14 is mounted in the fitting 6 and extends an appreciable distance above the bottom of the tube 4 where it receives the lower end 15 of the looped tube or siphon 16. 50 The end 17 of the siphon 16 is arranged substantially in the same plane as the end 15 but adjacent the bottom 5 and in free communication with the oil in the body 1. It will thus be seen that all of the oil passing 55 out through the pipe 14 must pass upwardly and then downwardly to the end 15.

When the rarefaction in the space 18, caused by the discharge of oil, becomes too great, air will be sucked in through pipe 14 and through the siphon 16 for partially destroying this vacuum whereby additional oil may be discharged.

This construction is particularly desirable on wrist pins and other parts of machinery where there is a rapid motion or a shaking or jerking motion. In an ordinary crank pin, if the tube 16 was omitted, the oil would feed too freely as a quantity would be forced out practically each time the cup changes its direction of movement. By providing the respective legs of the tube an equal length or substantially equal length, the oil in these tubes will balance each other and thereby permit a proper flowing when the cup has been jarred or when the parts have been sufficiently heated to expand the air in the space 18.

When the oil has been heated by reason of the heating of the bearing or for any other reason, the pressure in the space 18 will be raised and this pressure when assisted by the jarring action, will cause a proper feeding of oil. Usually, the air in the main body or space 18 of the cup extends as the parts become more or less heated and this over-balances the oil in the looped tube 16 whereby a certain quantity of oil is fed to the crank pin bearing or other bearing as required.

What I claim is:—

1. An oil cup, comprising a body for receiving a quantity of oil, a tubular member extending through said body having a plurality of apertures therein at different points, a partition member closing said tubular member below the last aperture, a discharge pipe extending from said tubular member, a looped tube or siphon carried by said tubular member positioned with one end discharging into said pipe and with the other end positioned in said body exteriorly of the tubular member.

2. An oil cup, comprising a body for receiving a quantity of oil, said body having a cap at one end for closing the same, a discharge tube mounted in the opposite end, said discharge tube extending from near the bottom of the body to the discharge point, a tubular member extending through said body and telescoping a short distance over said discharge tube, said tubular member having a plurality of apertures therein at

different points, a division member mounted in said tubular member between the inner end of said discharge tube and the nearest aperture in the tube to the discharge tube, and a substantially U-shaped siphon extending through two of the apertures in said tubular member with one end extending to

near the bottom of said body and the other extending through said tubular member and into the discharge tube, the lower ends of the siphon being in substantially the same plane. 10

LESLIE CARL DUTRO.
